CARTRIDGE-CONTROLLING MECHANISM
FOR REPEATING FIREARMSHarry L. Crockett, New Haven, Conn., assignor
to Western Cartridge Company, New Haven,
Conn., a corporation of Delaware

Application July 4, 1939, Serial No. 282,818

9 Claims.

(Cl. 42—17)

The present invention relates to improvements in repeating firearms and more particularly to mechanisms whereby the transfer of fresh cartridges from the magazines of firearms, is effected or controlled.

One of the objects of the present invention is to provide a superior cartridge-controlling mechanism for the purpose above referred to, which has capacity for reliable functioning without occasioning the jamming of the cartridges being fed or controlled.

Another object of the present invention is to provide a superior cartridge-control mechanism for repeating-firearms in which is embodied characteristics of positively preventing the undesirable tilting of one cartridge by another as the same are fed from the magazine of the firearm.

A further object of the present invention is to provide a superior cartridge-control mechanism for repeating-firearms in which is embodied a positive cartridge-control feature which, under one set of conditions, will impose positive restraint upon a cartridge and which, when conditions are altered, will provide the minimum of resistance to the further movement of the cartridge in question.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken view in side elevation of an upturn-and-pullback bolt-action repeating firearm embodying one form of cartridge-control mechanism embodying the present invention;

Fig. 2 is a broken view thereof mainly in vertical central-longitudinal section with portions shown in side elevation, the parts being shown in the positions due to them when the breech is in its breech-closing position and in readiness for firing;

Fig. 3 is a similar view but with more of the parts shown in side elevation and illustrating the parts in the positions which they assume when the breech-bolt is fully retired;

Fig. 4 is a transverse sectional view taken on the line 4—4 of Fig. 2;

Fig. 5 is a similar view taken on the line 5—5 of Fig. 3;

Fig. 6 is a view in side elevation of the unit 55

comprising the magazine-throat and the cartridge-detent, detached;

Fig. 7 is a top or plan view thereof;

Fig. 8 is a broken reverse plan view of the forward portion of the breech-bolt;

Fig. 9 is a perspective view of the cartridge-detent, detached; and

Fig. 10 is a perspective view of the magazine-throat, detached.

The repeating firearm herein chosen for illustration and description is of the so-called "upturn-and-pullback" bolt-action type and includes a tubular-receiver 15 into the forward end of which is threaded the rear end of a barrel 16 having a cartridge-chamber 16a therein. The said receiver 15 and barrel 16 are thus organized together and constitute what may be termed a "barrel-unit." The said receiver 15 is provided with an axial bolt-receiving chamber 17 and is cut away at its forward upper portion to provide an ejection-opening 18. The said ejection-opening 18 is in communication with the bolt-receiving chamber 17 in the receiver 15, as is also an L-shaped passage 19 in the rear portion of the said receiver, as is shown particularly well in Fig. 1.

The axial bolt-receiving chamber 17 in the tubular-receiver 15 receives a reciprocating cylindrically-contoured breech-bolt 20 having a laterally-offsetting operating-handle 21, the base of which latter is adapted to ride in the L-shaped passage 19 before referred to. The breech-bolt 20 is formed with a longitudinal firing-plunger passage 22 which is intersected at its forward end by a relatively-small firing-point passage 23. Reciprocable in the passage 22 in the breech-bolt 20 is a reciprocating firing-plunger 24 having a firing-point 25 movable through the firing-point passage 23 in the said breech-bolt.

Fixed within the hollow rear end of the breech-bolt 20 is an end-plug 26 against which is seated the rear end of a helical firing-spring 27. The forward end of the firing-spring 27 just referred to bears against the rear end of the firing-plunger 24 and exerts a constant effort to move the said firing-plunger forwardly.

The main portion of the firing-plunger 24 is substantially plate-like and is provided adjacent its rear end with a forwardly-facing cocking-shoulder 28 which is adapted to be engaged by a rearwardly-facing cocking-shoulder 29 formed upon the substantially-horizontal sear-arm 30 of a sear-and-trigger unit generally designated by the reference character 31. The said sear-and-trigger unit 31 includes also a substantially-

vertical trigger-arm 32 terminating at its lower end in a curved finger-piece 33. Mounted against the under side of the sear-arm 30 of the sear-and-trigger unit 31 is a safety-slide 34, which latter is not per se involved in the present invention and requires no detailed description other than to say that it is movable for locking and unlocking the firing mechanism of the firearm by a pivotal-lever 35 shown in Fig. 1.

The said sear-and-trigger unit 31 is mounted for pivotal movement upon a pivot-pin 36 carried by a wedge-shaped lug 37 fitting with a drive-fit within a similarly-shaped transverse groove 38 formed in the under side of the receiver 15 adjacent the rear end thereof.

Extending beneath the barrel 16 and beneath the forward portion of the receiver 15 is a magazine-tube 39 having a usual spring-pressed cartridge-follower 40 therein, which latter serves to press rearwardly upon such cartridges as may be located to its rear.

Projecting forwardly into the open rear end of the magazine-tube 39 is the tubular-stem 41 of a magazine-throat generally designated by the reference character 42 and which may be conveniently formed of sheet metal. The forward end of the tubular-stem 41 of the magazine-throat 42 is preferably formed, as shown, with an annular forwardly-and-outwardly sloping bevel 43 serving to guide cartridges from the magazine-tube 39 into the said tubular-stem, and thus rearwardly into the interior of the magazine-throat 42.

The magazine-throat 42 is formed with a pair of laterally-spaced-apart upwardly-extending side-panels 44 and 45 which extend upwardly into the interior of the receiver 15 through a longitudinal passage 46 (Figs. 4 and 5) formed in the bottom wall of the said receiver adjacent the forward end thereof and substantially directly below the ejection-opening 18 therein. The panel 44 just referred to, is shorter in a direction from front to rear than is the complementary panel 45 to accommodate adjacent its forward edge a detent-shifting tongue 47 which is formed integral with the magazine-throat 42 and slopes upwardly and outwardly for the purpose of shifting a cartridge-detent in the manner as will hereinafter appear. The side panel 44 is formed in its lower portion with a clearance-opening 48 which receives a detent-finger, as will appear from the following.

Immediately to the rear of its upwardly-projecting side panels 44 and 45, the magazine-throat 42 has its respective opposite side walls curved inwardly to provide two opposed cartridge-stop fingers 49 and 50. The last-mentioned cartridge-stop finger 50 is cut away at its forward portion to provide thereon a forwardly-facing cartridge-ejecting abutment 51.

The forward portion of the magazine-throat 42 is supported by having its tubular-stem 41 extended within the rear end of the magazine-tube 39, as before described, and the rear end of the said magazine-throat is rigidly supported in the firearm structure by a transverse pin 52 extending through perforations in the respective cartridge-stop fingers 49 and 50 thereof and into the adjacent portions of the receiver 15.

In addition to the features above described, the magazine-throat 42 is formed with a pair of rearwardly-projecting laterally-spaced-apart arms 53-53 between which extends, with capacity for rocking movement, a cartridge-carrier or elevator generally designated by the refer-

ence character 54. The said cartridge-carrier is mounted for pivotal movement between the arms 53-53 by means of a transverse pin 55 extending therethrough and through the said arms 53-53.

5 The respective opposite ends of the pivot-pin 55 project laterally beyond the said arms 53-53 to a degree sufficient to provide support for the complementary helical coils or loops 56-56 of a cartridge-elevating spring generally designated by the reference character 57. The said cartridge-elevating spring 57 is formed with a depending U-shaped arm 58 which joins the complementary coils or loops 56-56 and which engages with the rear face of the lower portion 15 of the cartridge-elevator 54 to yieldingly urge the same in a counter-clockwise direction around the pivot-pin 55. The said cartridge-elevating spring 57 is also formed with two rearwardly-extending arms 59-59 projecting respectively from the coils or loops 56-56 and engaged with the under face of the safety-slide 34. As thus constructed and arranged, the cartridge-elevating spring 57 exerts a constant but yielding effort to both lift the sear-arm 30 of the sear-and-trigger unit 31 and to turn the cartridge-elevator 54 in a counterclockwise direction for the purpose of sequentially elevating cartridges, all in a manner as will more fully hereinafter appear.

20 The upper rear portion of the cartridge-elevator 54 is provided with one or more lugs 60 adapted to be engaged for turning the said cartridge-elevator in a clockwise direction against the tension of the cartridge-elevating spring 57, by a forwardly-facing depressing-shoulder 61 formed on the breech-bolt 20 about midway the length thereof. If desired, though not essential, the breech-bolt 20 may also be provided with a rearwardly-facing abutment or shoulder 62 (Figs. 2 and 3) adapted to engage with the lug 60 on the cartridge-elevator 54 to assist the cartridge-elevating spring 57 in turning the said cartridge-elevator in a counterclockwise direction.

25 The forward edge of the main body of the cartridge-elevator 54 is curved concentrically with respect to the pivot-pin 55 and constitutes a releasable check or stop from the column of cartridges in the tubular magazine. The said cartridge-elevator 54 is formed with a longitudinal upwardly-opening pocket 63 receiving a tongue 64 hung upon a pivot-pin 65 carried by the said cartridge-elevator at a point remote from its own pivot-pin 55. The tongue 64 carried by the cartridge-elevator 54 is urged upwardly by a helical spring 66 bearing against the under side of the said tongue about midway the length thereof and seated in a spring-pocket 67 opening upwardly and intersecting the bottom wall of the larger pocket 63 in which the said tongue is located. To limit the upward 30 swing of the rear end of the tongue 64 with respect to the cartridge-elevator 54 by which it is carried, a pin-like stop-abutment 68 is mounted in the said cartridge-elevator and extends across the upper rear portion of the pocket 63 therein.

35 For the purpose of checking the rearward movement of cartridges as the same emerge from the magazine-tube 39 when the forward upper corner of the cartridge-elevator 54 is substantially fully depressed, the magazine-throat 42 is formed in either or both of its side walls with an in-bent cartridge-stop abutment 69 which acts as a stop for the cartridges in the manner illustrated in Fig. 2.

40 Movably associated with the right side wall of the magazine-throat 42 with capacity for both

vertical and lateral movement with respect thereto, is a cartridge-detent 70 which may be conveniently formed of sheet metal and which is provided at its rear end with a bearing-opening 71 which receives with a loose fit the left portion of the transverse pin 52 before referred to and which serves also to couple the rear portion of the magazine-throat 42 to the receiver 15. The freedom of fit between the bearing-opening 71 in the cartridge-detent 70 and the transverse pin 52 is sufficiently loose so that not only may the said cartridge-detent swing in a plane perpendicular with respect to the axis of the said transverse pin, but may also swing slightly laterally thereon, all for the purpose as will more fully hereinafter appear.

Formed integral with the lower edge of the cartridge-detent 70 and bent inwardly at a right angle thereto, is a cartridge-detent finger 72 which extends through the clearance-opening 48 in the side panel 44 of the magazine-throat 42 in position to move both vertically and laterally therein and to be engaged by the successive cartridges as the same move upwardly. The extreme forward end-portion of the cartridge-detent 70 is inset to provide an operating-tongue 73 preferably having its lower portion 74 sloping downwardly and inwardly as shown. The slope of the lower portion 74 just referred to, substantially corresponds to the slope of the inner face of the detent-shifting tongue 47 of the magazine-throat 42 so as to afford a smooth camming engagement therewith.

The upper edge 75 of the cartridge-detent 70 is positioned to be engaged by the under face of a longitudinal lug 76 depending from the under side of the forward portion of the breech-bolt 20 for the purpose as will more clearly hereinafter appear.

For purposes of description, let it be assumed that the parts are in the positions in which they are shown in Figs. 1, 2 and 4 and that three cartridges 77, 78 and 79 are in the gun structure. The cartridge 77 is in the cartridge-chamber 16a of the barrel 16 and the cartridge 78 is in the lower portion of the magazine-throat 42 with its rear end pressed against the cartridge-stop abutment 69 by pressure exerted by the spring-pressed cartridge-follower 40 through the intermediary of the cartridge 79 which latter is now partly in the magazine-tube 39 and partly in the magazine throat 42.

Now when the fingerpiece 33 of the sear-and-trigger unit 31 is pulled rearwardly, the cartridge 77 will be fired, following which the next normal operation is for the operator of the firearm to retire the breech-bolt 20 into the position in which it is shown in Fig. 3. In this manner the now-fired cartridge 77 will have been extracted from the cartridge-chamber 16a and ejected through the ejection-opening 18 of the receiver 15.

As the breech-bolt 20 moves rearwardly as above described, the lug 76 thereof will ride off from the upper edge 75 of the cartridge-detent 70 thus permitting the cartridge-elevator 54 acting through the cartridge 78 to force the said cartridge-detent to swing both outwardly and upwardly about the transverse pin 52 in a path determined by the coaction of the operating-tongue 73 in its engagement with the detent shifting tongue 47 of the magazine-throat 42. The resistance needed to be overcome in order to retire the cartridge-detent finger 72 of the cartridge-detent 70 out of the path of movement of the car-

tridge 78 is only the negligible weight of the said cartridge-detent 70, so that the cartridge-elevating spring 57 is enabled to elevate the said cartridge 78 from the position in which it is shown in Fig. 2 into the position in which it is shown in Fig. 3, without appreciable resistance.

It may be explained in this connection that as soon as the breech-bolt 20 is moved rearwardly, the depressing-shoulder 61 thereof will also be retired rearwardly thus relieving the cartridge-elevator 54 of restraint and permitting the cartridge-elevating spring 57 to assert itself (save in certain contingencies as will hereinafter appear) and swing the said cartridge-elevator 54 in a counterclockwise direction to effect the lifting or elevation of the cartridge 78 and the retirement of the cartridge-detent 70 as above described.

When the magazine-tube 39 is loaded to capacity it may be that the spring-pressed cartridge-follower 40 will press so firmly upon the column of cartridges as to so firmly pinch the cartridge 78 between the cartridge-stop abutment 69 and the cartridge 79 that, under some conditions, the cartridge-elevating spring 57 will not exert sufficient force to lift the cartridge 78 as above described. In this event, however, the rearward travel of the breech-bolt will bring the shoulder or abutment 62 at the rear end of the lug 76, into engagement with the upwardly-projecting portion of the cartridge-elevator 54 and thus provide sufficient force to swing the said cartridge-elevator in a counterclockwise direction and thus release the cartridge 78 from the grip in which it may be held between the next following cartridge 79 and the cartridge-stop abutment 69.

When now the breech-bolt 20 is moved toward its breech-closing position, the front face thereof will engage with the rim of the cartridge 78 which is now elevated as is shown in Fig. 3 and shift the same forwardly out from beneath the cartridge-stop fingers 49 and 50 of the magazine-throat 42 and will ultimately insert the said cartridge in the cartridge chamber 16a of the barrel 16.

As the breech-bolt is moved forwardly into its breech-closing position as just above described, the lug 76 thereof will engage and override the upper edge 75 of the cartridge-detent 70 to force the said cartridge-detent downwardly and inwardly in the event that gravity has not already accomplished its purpose. The inward movement of the cartridge-detent 70 will be effected as the same is moved downwardly by the engagement of the sloping lower portion 74 with the inclined detent-shifting tongue 47 of the magazine-throat 42. In any event, when the breech-bolt is in its forward or breech-closing position, the lug 76 of the breech-bolt 20 will overlie the forward portion of the cartridge-detent 70 and thus positively hold the same against either outward or upward movement so that its cartridge-detent finger 72 will be in position to prevent the next cartridge emerging from the magazine-tube 39 from becoming unduly tilted or cocked-up.

The latter part of the movement of the breech-bolt 20 into its breech-closing position will bring its depressing-shoulder 61 into engagement with the upper rear portion of the cartridge-elevator 54 and will swing the said cartridge-elevator in a clockwise direction against the tension of the cartridge-elevating spring 57 so as to restore the said cartridge-elevator to the position in

which it is shown in Fig. 2. As the upper forward corner of the cartridge-elevator 54 moves below the rim of the cartridge 79 the said cartridge will snap rearwardly under the force applied by the spring-pressed cartridge-follower 40, until its movement is halted by the engagement of the rim of the said cartridge with the cartridge-stop abutment 69 of the magazine-throat 42. It is now that the cartridge-detent 70 performs its function of preventing the cartridge 79 and those to follow in turn, from cocking-up or so tilting in the magazine-throat to such extent as to endanger their proper feeding to the cartridge-chamber 16a of the barrel 16. When the time comes for elevating the cartridge 79 the retirement of the breech-bolt 20 will have also retired the lug 76 thereof and thus released the cartridge-detent 70 which is now no longer required to perform any function until the next succeeding cycle of operation.

By providing the positively-actuated cartridge-detent 70 or its equivalent and permitting the same to have both vertical and lateral movement a very reliable, simple and effective structure is provided which insures the proper feeding of cartridges from a tubular-magazine to the cartridge-chamber of the firearm.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A tubular-magazine repeating-firearm including in combination: a barrel-unit having a cartridge-chamber therein; a tubular-magazine associated with the said barrel-unit and located below the cartridge-chamber therein; cartridge-elevating means operable to raise cartridges upwardly from the said tubular-magazine toward the cartridge-chamber in the said barrel-unit; a cartridge-detent also associated with the said barrel-unit and operatively mounted therein for movement alternately upwardly-and-outwardly and downwardly-and-inwardly with respect to the path of movement of cartridges as the same move from the said tubular-magazine to the cartridge-chamber of the said barrel-unit; and a breech-bolt reciprocating in a portion of the said barrel-unit and operable in the breech-closing movement thereof to cause the said cartridge-detent to be moved from its upwardly-and-outwardly-disposed position into its downwardly-and-inwardly-disposed position for restraining a cartridge against undue tilting as the same emerges from the said tubular-magazine.

2. A tubular-magazine repeating-firearm including in combination: a barrel-unit having a cartridge-chamber therein; a tubular-magazine associated with the said barrel-unit and located below the cartridge-chamber therein; cartridge-elevating means operable to raise cartridges upwardly from the said tubular-magazine toward the cartridge-chamber in the said barrel-unit; a cartridge-detent also associated with the said barrel-unit and operatively mounted therein for movement alternately upwardly-and-outwardly and downwardly-and-inwardly with respect to the path of movement of cartridges as the same move from the said tubular-magazine to the cartridge-chamber of the said barrel-unit; cam-means in-

clined inwardly and downwardly for guiding the said cartridge-detent inwardly when the same is moved downwardly; and a breech-bolt reciprocating in a portion of the said barrel-unit and operable in the breech-closing movement thereof to cause the said cartridge-detent to be moved from its upwardly-and-outwardly-disposed position downwardly into engagement with the said inwardly-and-downwardly-inclined cam-means to be moved inwardly by the latter into position for restraining a cartridge against undue tilting as the same emerges from the said tubular-magazine.

3. A tubular-magazine repeating-firearm including in combination: a barrel-unit having a cartridge-chamber therein; a tubular-magazine associated with the said barrel-unit and located below the cartridge-chamber therein; cartridge-elevating means operable to raise cartridges upwardly from the said tubular-magazine toward the cartridge-chamber in the said barrel-unit; a cartridge-detent also associated with the said barrel-unit and loosely pivoted about a substantially-horizontal axis extending crosswise of the firearm to permit the cartridge-detent to be alternately moved upwardly-and-outwardly and downwardly-and-inwardly with respect to the path of movement of cartridges as the same move from the said tubular-magazine to the cartridge-chamber of the said barrel-unit; and a breech-bolt reciprocating in a portion of the said barrel-unit and operable in the breech-closing movement thereof to turn the said cartridge-detent about its pivot-point from its upwardly-and-outwardly-disposed position into its downwardly-and-inwardly-disposed position for restraining a cartridge against undue tilting as the same emerges from the said tubular-magazine.

4. A tubular-magazine repeating-firearm including in combination: a barrel-unit having a cartridge-chamber therein; a tubular-magazine associated with the said barrel-unit and located below the cartridge-chamber therein; cartridge-elevating means operable to raise cartridges upwardly from the said tubular-magazine toward the cartridge-chamber in the said barrel-unit; a cartridge-detent also associated with the said barrel-unit and loosely pivoted about a substantially-horizontal axis extending crosswise of the firearm to permit the cartridge-detent to be alternately moved upwardly-and-outwardly and downwardly-and-inwardly with respect to the path of movement of cartridges as the same move from the said tubular-magazine to the cartridge-chamber of the said barrel-unit; cam-means extending inwardly and downwardly for guiding the said cartridge-detent inwardly when the same is moved downwardly; and a breech-bolt reciprocating in a portion of the said barrel-unit and operable in the breech-closing movement thereof to cause the said cartridge-detent to be moved from its upwardly-and-outwardly-disposed position downwardly into engagement with the said inwardly-and-downwardly-inclined cam-means to be moved inwardly by the latter into position for restraining a cartridge against undue tilting as the same emerges from the said tubular-magazine.

5. A tubular-magazine repeating-firearm including in combination: a barrel-unit having a cartridge-chamber therein; a tubular-magazine associated with the said barrel-unit and located below the cartridge-chamber therein; a magazine-throat structure located to the rear of the said tubular-magazine and having an upwardly-

opening interior chamber receiving cartridges from the said tubular-magazine and also having a side wall thereof provided with a clearance-opening for receiving a cartridge-stop finger of a cartridge-detent; cartridge-elevating means operable in the said magazine-throat structure to raise cartridges upwardly from the said magazine-throat structure toward the cartridge-chamber in the said barrel-unit; a cartridge-detent located adjacent the side of the said magazine-throat structure having the clearance-opening therein and having a cartridge-stop finger extending through the said clearance-opening, the said cartridge-detent being movable both vertically and laterally in respectively opposite directions to move its said cartridge-detent finger into and out of the path of cartridges as the same move from the lower portion of the said magazine-throat structure to the cartridge-chamber of the said barrel-unit; and a breech-bolt reciprocating in a portion of the said barrel-unit and operable in the breech-closing movement thereof to cause the said cartridge-detent to be moved both inwardly and downwardly to bring its cartridge-detent finger into position for restraining a cartridge against undue tilting in the said magazine-throat structure, when the said breech-bolt is moved into its breech-closing position.

6. A tubular-magazine repeating-firearm including in combination: a barrel-unit having a cartridge-chamber therein; a tubular-magazine associated with the said barrel-unit and located below the cartridge-chamber therein; a magazine-throat structure located to the rear of the said tubular-magazine and having an upwardly-opening interior chamber receiving cartridges from the said tubular-magazine and also having a side wall thereof provided with a clearance-opening for receiving a cartridge-stop finger of a cartridge-detent; cartridge-elevating means operable in the said magazine-throat structure to raise cartridges upwardly from the said magazine-throat structure toward the cartridge-chamber in the said barrel-unit; a cartridge-detent located adjacent the side of the said magazine-throat structure having the clearance-opening therein and having a cartridge-stop finger extending through the said clearance-opening, the said cartridge-detent being movable both vertically and laterally in respectively opposite directions to move its said cartridge-detent finger into and out of the path of cartridges as the same move from the lower portion of the said magazine-throat structure to the cartridge-chamber of the said barrel-unit; cam-means inclined inwardly and downwardly for guiding the said cartridge-detent inwardly when the same is moved downwardly; and a breech-bolt reciprocating in a portion of the said barrel-unit and operable in the breech-closing movement thereof to cause the said cartridge-detent to be moved from its upwardly-and-outwardly-disposed position downwardly for inward guidance by the said cam-means to move its cartridge-detent finger into position for restraining a cartridge against undue tilting in the said magazine-throat structure.

7. A tubular-magazine repeating-firearm including in combination: a barrel-unit having a cartridge-chamber therein; a tubular-magazine associated with the said barrel-unit and located below the cartridge-chamber therein; a magazine-throat located to the rear of the said tubular-magazine and having an upwardly-open-

ing interior chamber receiving cartridges from the said tubular-magazine and also having a side wall thereof provided with a clearance-opening for receiving a cartridge-stop finger of a cartridge-detent; cartridge-elevating means operable in the said magazine-throat structure to raise cartridges upwardly from the said magazine-throat toward the cartridge-chamber in the said barrel-unit; a cartridge-detent located adjacent the side of the said magazine-throat having the clearance-opening therein and having a cartridge-stop finger extending through the said clearance-opening, the said cartridge detent being movable both vertically and laterally in respectively opposite directions to move its said cartridge-detent finger into and out of the path of cartridges as the same move from the lower portion of the said magazine-throat to the cartridge-chamber of the said barrel-unit; a detent-guiding tongue carried by the said magazine-throat and inclined inwardly and downwardly for guiding the said cartridge-detent inwardly when the same is moved downwardly; and a breech-bolt reciprocating in a portion of the said barrel-unit and operable in the breech-closing movement thereof to cause the said cartridge-detent to be moved downwardly against the detent-guiding tongue of the said magazine-throat for inward guidance thereby to move its cartridge-detent finger into position for restraining a cartridge against undue tilting in the said magazine-throat.

8. A tubular-magazine repeating-firearm including in combination: a barrel-unit having a cartridge-chamber therein; a tubular-magazine associated with the said barrel-unit and located below the cartridge-chamber therein; a magazine-throat located to the rear of the said tubular-magazine and having an upwardly-opening interior chamber receiving cartridges from the said tubular-magazine and also having a side wall thereof provided with a clearance-opening for receiving a cartridge-stop finger of a cartridge-detent; cartridge-elevating means operable in the said magazine-throat structure to raise cartridges upwardly from the said magazine-throat toward the cartridge-chamber in the said barrel-unit; a transverse coupling-pin coupling the said magazine-throat to the said barrel-unit; a cartridge-detent located adjacent the side of the said magazine-throat having the clearance-opening therein and having a cartridge-stop finger extending through the said clearance-opening, the said cartridge-detent being loosely pivoted upon the said transverse coupling-pin with capacity for swinging movement in both vertical and lateral directions to move its said cartridge-detent finger into and out of the path of cartridges as the same moves from the lower portion of the said magazine-throat to the cartridge-chamber of the said barrel-unit; and a breech-bolt reciprocating in a portion of the said barrel-unit and operable in the breech-closing movement thereof to cause the said cartridge-detent both inwardly and downwardly to move its cartridge-detent finger into position for restraining a cartridge against undue tilting in the said magazine-throat.

9. A tubular-magazine repeating-firearm including in combination: a barrel-unit having a cartridge-chamber therein; a tubular-magazine associated with the said barrel-unit and located below the cartridge-chamber therein; a magazine-throat located to the rear of the said tubular-magazine and having an upwardly-open-

ing interior chamber receiving cartridges from the said tubular-magazine and also having a side wall thereof provided with a clearance-opening for receiving a cartridge-stop finger of a cartridge-detent; cartridge-elevating means operable in the said magazine-throat structure to raise cartridges upwardly from the said magazine-throat toward the cartridge-chamber in the said barrel-unit; a transverse coupling-pin coupling the said magazine-throat to the said barrel-unit; a cartridge-detent located adjacent the side of the said magazine-throat having the clearance-opening therein and having a cartridge-stop finger extending through the said clearance-opening, the said cartridge-detent being loosely pivoted upon the said transverse coupling-pin with capacity for swinging movement in both vertical and lateral directions to move its said

cartridge-detent finger into and out of the path of cartridges as the same move from the lower portion of the said magazine-throat to the cartridge-chamber of the said barrel-unit; and a 5 detent-guiding tongue carried by the said magazine-throat and inclined inwardly and downwardly for guiding the said cartridge-detent inwardly when the same is moved downwardly; and a breech-bolt reciprocating in a portion of the said barrel-unit and operable in the breech-closing movement thereof to turn the said cartridge-detent downwardly into engagement with the said detent-guiding tongue to be guided inwardly thereby and move its cartridge-detent finger into 10 15 position for restraining a cartridge against undue tilting in the said magazine-throat.

HARRY L. CROCKETT.
